DISPENSER FOR ADHESIVE TAPE AND THE LIKE

Ernst H. Hofmann-Igl, Munich, Germany, assignor to
P. Beiersdorf & Co. A.G., Hamburg, Germany

Application March 23, 1956, Serial No. 40,744

Claims priority, application France November 4, 1955

Term of patent 14 years

(Cl. D74—1)

Fig. 1

Fig. 2

Fig. 4

Fig. 1 is a side perspective view of a dispenser for adhesive tape showing my new design;

Fig. 2 is a top plan view thereof;

Fig. 3 is a side elevational view; and

Fig. 4 is a sectional view thereof taken along the line 4—4 of Fig. 3.

What I claim is:

The ornamental design for a dispenser for adhesive tape and the like, as shown.
